UNITED STATES PATENT OFFICE.

WILLIAM HANDLER, OF NEWARK, NEW JERSEY.

HANDLE.

1,350,650.

Specification of Letters Patent. Patented Aug. 24, 1920.

Application filed March 15, 1917. Serial No. 154,921.

To all whom it may concern:

Be it known that I, WILLIAM HANDLER, a citizen of the United States, and a resident of Newark, in the county of Essex and State 5 of New Jersey, have invented certain new and useful Improvements in Handles, of which the following is a description.

My invention relates to handles, and more particularly to an improved reinforced 10 handle for suit cases, bags and the like. One of the objects of my invention is to provide a handle of this character which is reinforced in a novel manner and so as to strengthen and stiffen the same where the 15 greatest strains and wear are imposed thereon, to thereby increase the life of the handle and prevent deformation thereof when subjected to heavy loads and much use.

Another object of my invention is to reinforce the handle in such a manner as to render the same, even when made of very cheap 20 and low grade materials, stronger and more durable than handles of this type made of the highest grade of materials as heretofore 25 constructed.

My invention also contemplates a construction wherein the reinforcing means serves to secure component parts of the 30 handle firmly and permanently together; and wherein said means is so disposed and secured in position that the handle may be made of the usual form and appearance.

A still further object of my invention is 35 to provide a construction wherein the foregoing results may be obtained without rendering the handle less easy to the grip and without involving the necessity of attaching the handle to the suit case, bag or the 40 like in any other than the usual manner, whereby the handle and its connection with the suit case or bag will have the proper and desired flexibility.

Other objects and features of my invention 45 reside in the details of construction and combinations of elements hereinafter more specifically described and claimed.

For a clearer understanding of my invention, attention is directed to the drawings 50 accompanying and forming a part of this specification, in the several figures of which like parts are designated by the same reference characters, and in which:

Figure 1 is a view in side elevation,

partly in section and partly broken away, 55 of a suit case provided with one form of handle embodying my invention;

Fig. 2 is a plan view, partly broken away, of the suit case and handle shown in Fig. 1;

Fig. 3 is a transverse sectional view of 60 the handle shown in Figs. 1 and 2; and

Fig. 4 is a view in side elevation, partly in section and partly broken away, of a modified form of my improved handle.

Referring to the drawing, and especially 65 to Figs. 1 to 3, reference character 1 represents a suit case and 2 the top thereof to which my improved handle A is attached. The handle A comprises the usual bottom or main portion 3 made up of the layers or 70 laminations 3' and the filler member or wickle B. The handle is provided with enlarged end portions 5 and with reduced portions 4 between the portions 5 and the central upwardly curved or bent enlarged 75 gripping portion. Reference characters 6, 6 represent the usual inverted U-shaped keepers, which are suitably secured to the suit case as by rivets 7, and which loosely take over the reduced portions 4 of the 80 handle A and serve to flexibly attach the latter to the suit case with the enlarged end portions 5 and said reduced portions 4 thereof lying flatly against the top 2. The filler member or wickle B is preferably com- 85 posed of a central longitudinally extending member 8 formed of a piece of steel wire or other stiff material, and a wrapping 9 formed of a triangular piece of paper or other suitable flexible material wound on 90 member 8 between its end portions to give the filler member B the proper shape. The wrapping 9 is so wound on member 8 that the member A will be thickest in the middle, as clearly shown in Figs. 1 and 2. In 95 making the handle A, the filler member or wickle B is applied to the central portion of the bottom member 3, which bottom member is slightly longer than the member B. A covering 10, preferably formed of a thin 100 piece of leather, is then fitted closely about the filler member B and the exposed portions of the member 3, with the exception of the enlarged end portions 5, the latter being either of leather or finished so as to have the 105 appearance of leather. The covering 10 is suitably secured in place on the handle, preferably by means of stitching, indicated

at S. This stitching preferably extends through the covering 10 above member 3 closely adjacent both sides of the member B, all the layers or laminations 3' of the bottom member 3, and the covering 10 on the lower side of member 3. The stitching S also preferably extends through layers 3' of the enlarged end portions 5 of member 3 adjacent the edges of the latter, as shown 10 in Fig. 2, and serves to hold these layers more firmly together. In the form of handle shown in Figs. 1 to 3, while the steel wire or other stiff central member 8 of the wickle B serves to strengthen and reinforce 15 the handle, I also preferably employ additional reinforcing means which preferably consists of a pair of strong stiff members 11, only one of which is shown, preferably formed of fairly heavy steel wire, and respectively applied to the handle adjacent 20 the opposite ends thereof. The members 11 are preferably applied to the bottom member 3 of the handle before the filler member B is applied thereto. The members 11 are 25 preferably, though not necessarily, respectively applied to the upper side of the reduced portions 4 of the member 3 and respectively extend longitudinally of the member 3 somewhat beyond such reduced portions. Each member 11 is provided with 30 end portions 12 extended downwardly through all the layers 3' of the bottom member 3 and which have their ends turned over and clenched against the under side of said 35 bottom member, as indicated at 13 in Fig. 1, whereby the members 11 are securely held in place and also serve to fasten the layers 3' more firmly together. In order to more firmly hold the members 11 in place, the 40 ends 13 thereof are preferably clenched toward each other as shown.

After the covering 10 has been stitched onto the handle, the latter is worked, in any suitable manner, to the finished form shown, 45 with the side portions of the bottom member 3 pressed up closely about the sides of the filler member B and with the central portion of the handle bent and shaped to conform to the grip. The handle is then fastened to the suit case or bag 1 by the keepers 6 in the usual manner. The member 8 is 50 preferably of such length that the ends thereof are concealed by the keepers 6. The ends of covering 10 also preferably terminate at the reduced portions 4 of the handle, so that they will be concealed by keepers 6. It will be apparent that the strong steel 55 or other reinforcing members 11 strengthen the handle at the points of greatest wear and strain and coöperate with the member 8 to produce the results and objects above stated.

In the handle C shown in Fig. 4, the members 11 are dispensed with and in place of the member 8 shown in Figs. 1 to 3, I 60 employ a fairly heavy piece 15 of steel

wire or other suitable stiff material. The wire 15 extends beyond the ends of the wrapping 9 a somewhat greater distance than the member 8 of Figs. 1 to 3, and the extending portions closely engage the upper side of the 70 end portions of member 3. At each end the wire 15 is extended downwardly, as shown at 16 through the layers or laminations 3' of member 3 and clenched back against the bottom or under side of the latter, as shown 75 at 17. Otherwise, the handle C is of the same construction as handle A shown in Figs. 1 to 3.

While I have shown and described two preferred forms of my improved handle, it 80 is to be understood that various changes may be made in the form, size and arrangement of the parts thereof without any departure from the spirit of my invention and the scope of the appended claims. 85

Having now described my invention, what I claim and desire to protect by Letters Patent is as follows:—

1. A handle comprising a bottom member and a filler member applied to the bottom member intermediate the ends thereof, said filler member having a stiff reinforcing member extending longitudinally thereof and inclosed therewithin, said handle having reduced portions adjacent its ends whereby 90 it is adapted for connection with a bag or the like by keepers applied to such bag and taking loosely over such reduced portions, and reinforcing means anchored only and directly to said bottom member and extending longitudinally of the handle at said portions. 95

2. A handle comprising a bottom member having reduced portions adjacent its ends for connection with a bag or the like, and a filler member applied to the bottom member intermediate the ends thereof, said filler member comprising a stiff metallic member extending longitudinally thereof and flexible material surrounding said metallic member, and a pair of longitudinally extending metallic reinforcing members respectively applied to said reduced portions on one side of the bottom member, each of 100 said reinforcing members having end portions extending transversely through said bottom member, the ends of said end portions being anchored to the bottom member on the other side thereof. 110

3. A handle comprising a bottom member having reduced portions adjacent its ends for connection with a bag or the like, and a filler member applied to the bottom member, said filler member having a stiffening member inclosed therewithin, and longitudinally extending reinforcing means applied to said reduced portions on one side of the bottom member, said reinforcing means having portions extending transversely through said bottom member, the ends of 125 130

said transversely extending portions being anchored only and directly to the bottom member on the other side thereof.

4. A handle comprising a bottom member having reduced portions adjacent its ends for connection with a bag or the like, a filler member applied to the bottom member and having a stiff reinforcing member extending longitudinally thereof and in-
10 closed therewithin, and reinforcing means

anchored to the bottom member and extending longitudinally of the handle at said portions.

This specification signed and witnessed this 13th day of March, 1917.

WM. HANDLER.
